(57) **CLAIM**

The ornamental design for a cap of ink bottle for printer, as shown and described.

DESCRIPTION

FIG. 1 is a perspective view of the cap of ink bottle for printer;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof; and,

FIG. 8 is a cross-sectional view thereof taken along line 8-8 in FIG. 2.

The evenly spaced broken lines depict unclaimed parts of the cap of ink bottle for printer and form no part of the claimed design. In FIG. 2, the dash-dot-dash broken lines represent a sectional designation that forms no part of the claim.
